DESIGN FOR A HAIR DRYING CABINET

Philip H. Ordin and Jack Barney Ordin,
Los Angeles, Calif.

Application November 26, 1935, Serial No. 59,775

Term of patent 14 years

To all whom it may concern.:

Be it known that we, Philip H. Ordin and Jack Barney Ordin, citizens of the United States, residing in Los Angeles, in the county of Los Angeles and State of California, have invented a certain new original, and ornamental Design for Hair Drying Cabinets, of which the following is a specification, reference being had to the accompanying drawing, forming part thereof.

The figure is a perspective view of a hair drying cabinet showing our new design.

The other side of the cabinet is substantially like the side shown.

We claim:

The ornamental design for a hair drying cabinet, substantially as shown and described.

PHILIP H. ORDIN.
JACK BARNEY ORDIN.
